STEPHEN C. RADFORD, OF OSHKOSH, WISCONSIN

SYSTEM FOR UTILIZING FLUID PRESSURE

Application filed May 26, 1928. Serial No. 280,757.

This invention relates to improvements in system for utilizing fluid pressure and latent heat in condensed steam for pressure purposes.

In the ordinary power plants only a small percentage of the heat units of the common fuels are converted into power, and the balance of power of the units is lost through the stack gases, exhaust steam, friction, radiation, etc.

It is one of the objects of the present invention to overcome the before mentioned objectionable features and provide a system of utilizing fluid pressure in which the pressure medium or heat units are used a plurality of times to extract all of the heat and pressure units therefrom.

A further object of the invention is to provide a system for utilizing fluid pressure in which boilers, engines, an air compressor, a steam condenser, an air heater, a super heater and a pump are connected together in a manner to utilize a larger percentage of the power or heat than is usual in common practice.

A further object of the invention is to provide system of utilizing fluid pressure which is very simple, is easily carried out, and is well adapted for the purpose described.

With the above and other objects in view, the invention consists of the improved system for utilizing fluid pressure and its parts and combinations as set forth in the claims, and all equivalents thereof.

The accompanying drawing shows a diagrammatic view of the system for utilizing fluid pressure.

Referring to the drawing, the numeral 5 indicates a main steam boiler, and 6 a super heater which may be of any ordinary type for super-heating steam for use in an engine 7. The engine 7 is connected to the super heater 6 and the boiler 5 by a pipe 8 controlled by a valve 9. The steam in passing from the boiler to the engine 7 flows through the super heater 6 and is super-heated thereby. An exhaust pipe 10 connected to the exhaust opening of the engine 7 extends and is connected to a closed type condenser 11 and the water of condensation from said condens-

er flows through a pipe 12 to a pump 13. The operation of the pump will force the water of condensation through the pipe 14 back to the boiler 5.

A heat exchanger 15 of the closed type is connected, by means of a pipe 16, to the pipe 14 or pump 13, and receives water of condensation therefrom, which is vaporized in said heat exchanger 15 and returns to the super heater 6 by a pipe 17. A check valve 18 is interposed between portions of said pipe 17 to prevent the return of steam to the heat exchanger 15. Valves 14' and 16' are provided for controlling the flow of water from the pump 13.

An air compressor 19 heats air or any inert non-inflammable gas, which is preferably free from moisture, by compression, and forces said heated and compressed air through the pipe 20 and into the heat exchanger 15 and vaporizes the hot condensed water within the tubes of the heat exchanger. The hot compressed air imparts sufficient heat to the hot water to vaporize it, and then flows through a valved pipe 15' from the heat exchanger into an air engine 21, and the pressure of the air is utilized to drive said air engine or other device. The air in passing through the heat exchanger 15 will lose a part of its heat, and in expanding in the air engine will become comparatively cool, and from the engine will pass through the pipe 22 to the condenser 11 and serve as the cooling medium for the exhaust steam passing through the tubular portion of the condenser 11. In passing through the condenser, the air or other fluid absorbs heat from the exhaust steam, and by means of the pipe 23, the partly heated air flows from the condenser to the air compressor 19 before mentioned. Supplemental pipes 24 are connected to the pipe 23 and include an air heater 25 to permit additionally heating the air if desired. Valves 26 and 27 provide for controlling the flow of air from the condenser directly to the air compressor or to the air heater and then to the air compressor, or the valves may be left open to permit part of the air to flow to the heater before entering the compressor. The super heater 6 and the air

heater 25 are preferably placed in the chimney flue 28 of the boiler 5 to receive heat from the hot gases of combustion from the heating means of the boiler 5.

5 In use, the steam from the boiler 5 will actuate the engine 7, and the exhaust steam from the engine will flow through the condenser and be condensed by the cool exhaust air from the air engine. The water of condensation will be returned to the boiler 5 and heat exchanger 15 by the pump 13. The cooling air after absorbing heat from the exhaust steam will be further heated in the heater 25 and will then be further compressed 10 and heated by the compressor 19. The hot compressed air is then directed into the heat exchanger 15 to utilize the heat in the air to heat the water therein and generate steam which will supplement the steam of the boiler 5. The pressure of the compressed air after 15 it has imparted its heat to the water in the heat exchanger 15 is utilized to drive the air engine 21. Furthermore, the air is quickly expanding in the air engine will become comparatively cool and this coolness is utilized 20 in the condenser as before described. Part of the water of condensation from the condenser 11 will be forced by the pump into the heat exchanger 15, turned into steam and the 25 steam will flow to the boiler 5 or the super heater 6 for use in the engine 7 or any other power producing unit. The power from the main and secondary engine may be used in any manner desired.

30 35 From the foregoing description it will be seen that the system for utilizing fluid pressure is very simple and is well adapted to utilize a large amount of the heat and pressure developed in the system.

40 What I claim as my invention is:

1. In combination, a steam engine, an air compressor, an air engine, a boiler, a superheater for steam delivered from said boiler adapted to supply superheated steam for 45 driving said steam engine, a condenser for the exhaust steam delivered from said steam engine, means for delivering water of condensation from said condenser to said boiler, an air heater operable by gases of combustion 50 from said boiler, means for conducting heated air from said air heater to said air compressor, a heat exchanger also adapted to receive water of condensation from said condenser, means for delivering said heated air 55 in compressed and further heated condition from said compressor to said heat exchanger to convert the water of condensation delivered to the latter into steam, means for delivering said steam to the inlet of said superheater, means for delivering the air from said 60 heat exchanger at high pressure but at reduced temperature and pressure to said air engine to drive the same, means for delivering the exhaust air from said air engine to 65 said condenser for cooling purposes, and

means for delivering said air from said condenser to said air heater to be heated and subsequently compressed for utilization in said heat exchanger, air engine and condenser.

70 2. In combination, a steam engine, an air compressor, an air engine, a boiler, a superheater for steam delivered from said boiler adapted to supply superheated steam for driving said steam engine, a condenser for the exhaust steam delivered from said steam engine, means for delivering water of condensation from said condenser to said boiler, an air heater operable by gases of combustion from said boiler, means for conducting heated air from said air heater to said air compressor, a heat exchanger also adapted to receive water of condensation from said condenser, means for delivering said heated air in compressed and further heated condition from said compressor to said heat exchanger to convert the water of condensation delivered to the latter into steam, means for delivering the air from said heat exchanger at high pressure but at reduced temperature and pressure to said air engine to drive the same, means for delivering the exhaust air from said air engine to said condenser for cooling purposes, and means for delivering said air from said condenser to said air heater to be heated and subsequently compressed for utilization in said heat exchanger, air engine and condenser.

80 85 In testimony whereof, I affix my signature.
